UNITED STATES PATENT OFFICE.

SAMUEL WALKER, OF NEW YORK, N. Y.

CAP FOR PENS.

Application filed August 13, 1923. Serial No. 657,128.

To all whom it may concern:

Be it known that I, SAMUEL WALKER, a citizen of the United States, and a resident of the city of New York, borough of Queens, in the county of Queens and State of New York, have invented a new and Improved Cap for Pens, of which the following is a full, clear, and exact description.

This invention has relation to covers for pens and has particular reference to an improvement in caps which are especially designed for use in connection with fountain pens.

At the present time fountain pen nibs are covered by a cap which is either frictionally or threadedly fitted over the nib end of the barrel and necessitates the entire removal of the same from the barrel and its placement on the opposite end when it is desired to expose the nib for use.

To overcome the above recited objections and disadvantages, it is therefore the principal object of the present invention to provide a cap for fountain pens which cap is axially slidable on the nib end of the barrel, whereby the same may be retracted or moved upwardly on the barrel to expose the nib for use, thus eliminating the necessity of entirely removing the cap.

As a further object the invention contemplates a cap for fountain pens which is of tubular formation and telescopically arranged over the nib end of the barrel, the said tubular body being provided with means for normally closing the outer end, which means upon inward telescopic movement of the tubular body over the barrel effects an automatic opening thereof to expose the nib for use and which means upon outward telescopic movement is automatically closed to cover the nib.

As a still further object the invention contemplates in combination with a cap of the character set forth, means for retaining the cap respectively in its covering or uncovering positions, against accidental displacement.

Another object in view is to provide a cap of the character set forth which is radially contractible, whereby the same is capable of use in connection with pen barrels of various diameters.

The invention furthermore contemplates a cap of the character set forth, which is extremely simple in its construction, inexpensive to manufacture and produce and

which is thoroughly reliable and highly efficient in its purpose.

With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawings—

Figure 1 is a longitudinal sectional view through a cap constructed in accordance with the invention, the same being taken approximately on the line indicated at 1—1 in Fig. 3, and illustrating the same applied and in nib covering position.

Fig. 2 is a similar view with the cap moved to a position for uncovering the nib.

Fig. 3 is a plan view.

Fig. 4 is a transverse sectional view through the cap taken approximately on the line 4—4 of Fig. 1.

Fig. 5 is a plan view of the blank from which the cap is constructed prior to the bending of the same into finished shape.

Referring to the drawings by characters of reference, A designates the barrel of a fountain pen and B the nib. The cap or cover for the nib which constitutes the invention consists of a tubular split resilient body 10 and ends 11 and 12 of which are overlapped. The said tubular body due to its inherent resiliency normally tends to retract radially on the barrel of the pen when applied thereto whereby the same is capable of fitting barrels of various diameters. At its inner end the tubular body 10 is open to slidably or telescopically fit over the nib end of the pen barrel A. At its outer end the tubular body 10 has connected thereto a pair of semi-conical sections 13 and 14 by a means of resilient connecting portions 15 and 16 which operate to advance and retain the sections 13 and 14 in mating relation for closing the outer end of the body 10 when the said body is moved axially outward on the nib end of the barrel a sufficient distance to allow the sections 13 and 14 to clear the point of the nib B.

In the preferred embodiment of the invention as illustrated the tubular body 10, the semi-conical sections 13 and 14 and the connecting

portions 15 and 16 are integral and are stamped and bent from a single sheet of material, the blank of which is illustrated in Figure 5. In order to form the device from the blank as illustrated in Figure 5 the side edges of one end are cut away at an angle as at 17 and a V-shaped portion 18 is cut out of said end with the apex 19 of said V-shaped portion disposed substantially at the transverse center of the blank and in alignment with the juncture 20 of the inclined cutaway edges 17. From the junctures 20 the blank is slit inwardly and at an angle as at 21 and from the apex 19 the blank is slit outwardly and at an opposite angle as at 22. Adjacent terminals of the slits 21 and 22 communicate with the longitudinal parallel slits 23 which form the resilient connected portions 15 and 16. The slits 21 and 22 together with the V-shaped cut out portion 18 and the inclined side edges 17 define the material for forming the semi-conical sections 13 and 14, while the remainder of the blank constitutes the material for forming the tubular split body 10. The body 10 is formed with an outwardly pressed circumferential bead 24 which defines on the inner side of the body an annular groove or recess 25. The pen barrel A is provided with outwardly projecting teats 26 and 27 longitudinally spaced thereon for cooperation with the annular groove or recess 25 to retain the tubular body 10 in axially shifted position.

In use and operation of the device, when the body A is shifted axially outward to a point where the semi-conical sections 13 and 14 clear the point of the nib B as illustrated in Figure 1, the inherent resiliency or springiness of the connecting portions 15 and 16 operate to advance and retain said sections in close relation whereby the nib is covered and housed when the pen is not in use. In this position the annular groove or recess 25 engages over or receives the teat 26 to retain the cap in this position. When it is desired to use the pen the nib B is ex-

posed by axially shifting the tubular body 10 of the cap inwardly. The inward shifting movement causes the relative separation of the sections 13 and 14 by engagement of the nib therewith and as the tubular body is retracted or moved radially inward on the pen barrel A the annular groove or recess 25 finally engages or receives the inner teat 27 with the sections 13 and 14 wholly retracted from the nib end of the pen, as illustrated in Figure 2. A reverse outward movement effects the automatic closure of the sections 13 and 14 as will be clearly understood.

It will thus be seen that an extremely simple and inexpensive closure cap for pens has been provided which eliminates the necessity of removing the cap to expose the nib for use.

I claim:

1. A cap for the nib end of pens formed of a single piece of material bent to form a tubular body portion with its edges in overlapped relation and provided at one end with semi-conical nib enclosing sections connected with the body by resilient portions struck up from the body and sections, the portions of the body and sections at each side of the resilient connecting portions being inclined and fitting against one another.

2. A blank for formation into a pen cap, having the corners of one end cut away at an angle, the intermediate portion of said end having a V-shaped notch, the apex of which is disposed inwardly and in transverse alignment with the inner end of the cut away corners, said blank having pairs of spaced longitudinal parallel slits and pairs of transverse parallel slits, the latter slits extending respectively between the apex and the innermost slit of each pair of longitudinal slits, and between the outermost slit of each longitudinal pair and the inner ends of the cut away corners.

SAMUEL WALKER.
